APPARATUS FOR REJECTING APERTURED COINS

John Gottfried, St. Louis, Mo., assignor to National Re-jectors, Inc., St. Louis, Mo., a corporation of Missouri

Application March 14, 1951, Serial No. 215,436

6 Claims. (Cl. 194—97)

This invention relates to improvements in coin separators. More particularly, this invention relates to improvements in feelers than can be used with coin separators to detect and restrain coins which have openings therethrough or have appreciable surface deformations.

It is therefore an object of the present invention to provide an improved feeler which can be used with a coin separator to detect and restrain coins which have openings therethrough or have appreciable surface deformations.

In the operation of coin separators, coins are introduced into the coin slots of those separators, and thereafter those coins work their way toward the coin boxes of those separators. As they move toward the coin boxes of the coin separators, the coins are customarily tested in a number of ways to determine their authenticity. For example, the coins are tested as to the electrical conductivity of the metals of which they are composed. The diameters and the thicknesses of the coins also are tested. In addition, the coins are tested for the presence of openings therethrough or appreciable surface deformations. In the event a coin is tested and found wanting, that coin must be directed immediately toward the rejected coin chute or must be restrained until a clearing lever can free it for movement toward the rejected coin chute.

A number of prior coin separators have been equipped with feelers which were intended to detect and restrain coins which had openings therethrough or had appreciable surface deformations. However, the feelers of those coin separators were not, either from the standpoint of cost, efficiency, or certainty of operation, completely satisfactory. The improved feeler, for coin separators, that is provided by the present invention is low in cost, high in efficiency, and certain of operation.

To be efficient, the feeler of a coin separator must engage and explore a considerable portion of the area of each coin introduced into the coin separator, and yet that feeler must not appreciably impede the movement of authentic coins to the coin boxes of those coin separators. The improved feeler provided by the present invention does this by limiting the instantaneous contact between the feeler and the coin to point contact, and by having the points of contact between feeler and coin define a bent path. The point contact limits the frictional forces which could retard movement of the coin toward the coin box, and the bent path assures the exploration of a greater proportion of the area of the coin than a straight path could assure. In this way the feeler provided by the present invention assures the desired exploration of the surface of the coin and yet does not impede the movement of authentic coins toward the coin box. It is therefore an object of the present invention to provide a feeler, for coin separators, which has point contact with each coin introduced into the separator, and which explores a bent path on the surface of each such coin.

To be certain of operation, a feeler for coin separators must either direct improper coins to the rejected coin chute or must restrain those coins until a clearing lever

2

can free them for movement to the rejected coin chute. This is not easily done since the persons who introduce the coins into the coin separators may, in the belief that those separators are not operating properly, nudge the coin separators or may even strike them sharply. Such nudging or striking of the coin separators could tend to loosen the restraining forces which the feelers apply to improper coins; and it might possibly free those coins from the feelers and permit them to pass to the coin boxes of the coin separators. This, of course, would be objectionable. The present invention obviates these objections by providing a feeler, for a coin separator, which maintains its restraining force on improper coins irrespective of any nudges or blows that are applied to the coin separator. It is therefore an object of the present invention to provide a feeler, for a coin separator, that is not disabled by the nudging or striking of the coin separator.

The feeler provided by the present invention is enabled to do this because the coin-engaging portion thereof is inclined transversely of the passageway in the coin separator for the coins, and it is directed oppositely of the normal direction of movement of the coins in that passageway. Consequently, when the coin-engaging portion of the feeler engages and restrains an improper coin, it wedges that coin against the side of the passageway. If the coin separator is nudged or struck, the feeler will not free the coin; instead, it will only wedge it more tightly against the side of the passageway. In this way, the feeler provided by the present invention positively restrains improper coins. It is therefore an object of the present invention to provide a feeler, for a coin separator, which has the coin-engaging portion thereof inclined transversely of the coin passageway and directed oppositely of the normal direction of movement of the coins in that passageway.

The feeler provided by the present invention is held by a fixed pivot, and it is provided with a weight that biases its coin-engaging portion for movement into the coin passageway of the coin separator. The fixed pivot for the feeler is desirable since it confines the weight to a path throughout which the weight can provide a substantially uniform bias for the feeler. With this arrangement, the weight is able to provide the coin-restraining force as well as the force which moves the coin-engaging portion of the feeler into the passageway. It is therefore an object of the present invention to provide a fixed pivot for the weighted feeler of a coin separator.

The feeler provided by the present invention is positioned adjacent the cradle which receives the coins and tests their diameters; that cradle responding to the weight of properly-sized coins to move and thus permit those coins to advance through the passageway. The cradle holds the coin-engaging portion of the feeler out of the passageway until a coin engages the cradle and causes it to move relative to the feeler. As a result, the feeler engages coins that are moving relative to the coin engaging portion of that feeler; and this is desirable since dynamic frictional forces are smaller than static frictional forces. This makes it possible to use larger biasing forces on the feeler without unduly impeding the movement of proper coins to the coin box. It is therefore an object of the present invention to provide a feeler, for a coin separator, that is held out of engagement with the coins until those coins are moving relative to the coin-engaging portion of that feeler.

Other and further objects and advantages of the present invention should become apparent from an examination of the drawing and accompanying description.

In the drawing and accompanying description a preferred embodiment of the present invention is shown and described but it is to be understood that the drawing and accompanying description are for the purpose of

illustration only and do not limit the invention and that the invention will be defined by the appended claims.

In the drawing:

Fig. 1 is a partially broken-away, side elevational view of a coin separator embodying the feeler provided by the present invention.

Fig. 2 is a partially-sectioned plan view of the coin separator shown in Fig. 1, and it is taken along the planes indicated by the line 2—2 in Fig. 1.

Fig. 3 is a larger view of the cradle and feeler of the coin separator shown in Figs. 1 and 2, and it shows that cradle in coin-transferring position.

Fig. 4 is a view of the cradle and feeler of Fig. 3, and it shows that cradle in coin-receiving position.

Fig. 5 is a cross sectional view taken along the plane indicated by the line 5—5 in Fig. 4, and

Fig. 6 is a side elevational view of a coin, and the dashed line thereon indicates the line which is explored by the feeler of the present invention.

Referring to the drawing in detail, the numeral 10 generally denotes the frame of a coin separator that is made in accordance with the principles and teachings of the present invention. A gate, which is movable relative to the frame 10, is denoted by the numeral 12; and it is held for swinging movement relative to the frame 10 by the pivot 14. A helical spring 16 encircles the pivot 14 and biases the gate 12 for movement into parallel relation with the frame 10. A spacer 18 is formed on the inner face of the gate 12, and that spacer bears against the frame 10 and maintains a minimum distance of predetermined size between the gate 12 and the frame 10. An entrance 20 is provided on the gate 12, and that entrance guides the coins into the coin passageway of the coin separator provided by the present invention.

A fixed pivot 22 is formed on the gate 12, and that pivot rotatably supports a cradle 24. The cradle 24 has projections 26 thereon which are spaced apart a distance just slightly less than the diameter of a properly sized coin which is to be accepted by the coin separator. This spacing of projections 26 enables cradle 24 to act as a coin-sizing gauge. A weight 28 is mounted on the cradle 24, and that weight biases the cradle 24 for rotation to the position shown in Figs. 1 and 4. Spaced slots 30 are provided in the gate 12 to permit the projections 26 on the cradle 24 to extend into the coin passageway of the coin separator. The projections 26 are so disposed relative to the pivot 22 that they will hold a properly sized coin with its center of gravity to the right of pivot 22; and such coin will, if of the proper weight, be able to overcome the force applied to cradle 24 by the weight 28 and thus cause that cradle to rotate in a clockwise direction. The slots 30 are elongated to permit the projections 26 to move freely as the cradle 24 moves to the coin-transferring position shown in Fig. 3. A camming edge 32 is provided on the cradle 24 intermediate the right hand projection 26 and the pivot 22.

A generally vertical slot 34 is formed in the gate 12 adjacent the cradle 24. A fixed pivot 36 is disposed below and to the left of the slot 34, and that fixed pivot supports a feeler 37. This feeler has a portion which spans the two arms of the fixed pivot 36, it has a weight-carrying portion at the lower end thereof that carries a weight 40, and it has a coin-engaging portion 38 at the upper end thereof. The weight 40 on the weight-carrying portion of the feeler 37 biases that feeler for rotation in a clockwise direction, as viewed in Fig. 5. Such biasing action tends to force the coin-engaging portion 38 of feeler 37 into engagement with a coin in the passageway of the coin separator. That coin-engaging portion of feeler 37 is arcuate and it has a small radius of curvature; hence it will experience point contact with any such coin. Point contact is more desirable than line contact because it reduces the frictional forces applied to the coin by the feeler, and thus avoids needless slowing down of the coin.

The coin-engaging portion 38 of feeler 37 is adjacent the camming edge 32 of cradle 24. When the cradle 24 is in the coin-receiving position shown in Figs. 1 and 4, the camming edge 32 of that cradle will underlie the coin-engaging portion 38 of feeler 37 and hold that coin-engaging portion out of the coin passageway. As a result, the cradle 24 is not only a coin-sizing gauge and a weight-tester, but it is a detent; serving to hold the coin-engaging portion 38 of feeler 37 out of the coin passageway.

When the cradle 24 rotates in clockwise direction to its coin-transferring position, as it will do whenever it receives a coin of the proper size and weight, the camming edge 32 of that cradle will move out of engagement with the coin-engaging portion 38 of feeler 37. Thereupon, that portion will respond to the action of weight 40 and move inwardly through slot 34 into the coin passageway. Whenever the cradle 24 returns to its coin-receiving position, the camming edge 32 of that cradle will engage the coin-engaging portion 38 of feeler 37 and move it out of the coin passageway.

A runway 42 is formed on the rear surface of gate 12 adjacent the lower end of the right hand slot 30. This runway will receive coins which are sized and weighed by cradle 24 and are then rotated past feeler 37 to a point immediately adjacent the upper end of runway 42. Those coins roll off of the right hand projection 30 of cradle 24 and will roll along runway 42.

In rolling along that runway, the coins will be acted upon by a permanent magnet 44 which is disposed on frame 10 adjacent the runway 42. A bent plate 145 is secured to the magnet 44, and the lower part thereof is spaced from that magnet to provide a passage for coins; and that plate completes the magnetic circuit of the magnet 44. The magnet 44 will generate eddy currents within the coin, and the resulting magnetic field will interact with the magnet's field to retard the rate of movement of the coins. The exact retardation applied to any coin by the interacting magnetic fields will be proportional to the electrical conductivity of the metals of which the coin is composed. If a coin has the desired conductivity, it will leave the runway 42 with sufficient speed to strike anvil 45 and rebound across the frame 10 and into the gap between stop 46 and deflector 47; that coin following a generally horizontal arcuate path. Deflector 47 will then direct the coin downwardly along the arcuate runway 49 to coin exit 50. Thereafter that coin can be directed toward switches or actuators of suitable coin-operated devices by guides, not shown. Those guides will finally direct the coin to the coin box.

If the coin has too low a conductivity, its speed will not be retarded appreciably. That coin will, therefore, roll off of the runway 42 with sufficient speed to strike anvil 45 and rebound across and upwardly into engagement with the stop 48. Engagement of such coin with stop 48 will force that coin to bound downwardly and to the right where it will strike deflector 51 and will be directed onto runway 52. It will then roll along runway 52 to the rejected coin chute 53. The cut-away partition 54 separates the anvil 45 and deflector 47 and runway 49 from the runway 52; deflector 51 extending through the cut-away portion of that partition to underlie the path between anvil 45 and deflector 47.

If the coin has too high a conductivity, its speed will be retarded to such an extent that the coin will either fall toward deflector 51 without reaching anvil 45 or will strike anvil 45 and rebound with insufficient force to reach the gap between stop 46 and deflector 47. Instead, that coin will only be able to reach stop 46; and that stop will direct the coin backwardly and downwardly toward deflector 51. Such coin will pass to the rejected coin chute 53 via deflector 51 and runway 52.

A pusher bracket 56 is supported on the gate 12 by lugs 58 which extend into openings in the gate 12, and by a spring 60 which urges the bracket 56 against a spacer 62

carried by the frame 10. The end of the bracket 56 is normally held out of the coin passageway by the spacer 62 but it serves, whenever the gate 12 is moved away from the frame 10, to strip any coins from the coin-engaging portion 38 of feeler 37.

When a coin of the proper size, weight and electrical conductivity is introduced through the entrance 20, that coin will fall downwardly and engage the projection 26 of the cradle 24. That coin will be held by those projections and will cause that cradle to rotate in a clockwise direction. As soon as the cradle 24 starts to move, the camming edge 32 of that cradle will move out of engagement with the coin-engaging portion 38 of feeler 37; permitting the weight 40 to rotate that feeler until the coin-engaging portion 38 thereof enters the passageway. The cradle 24 and the feeler 37 are disposed in close juxtaposition, so the cradle will place a coin in register with the coin-engaging portion 38 before it permits the feeler 37 to move. In this way, undesired interruption of movement of proper coins is prevented; the coin passageway being kept clear, as by holding the feeler 37 back, until the coin is in register with the coin-engaging portion 38 of that feeler, whereby the leading edge of a coin can not strike and jam against the feeler 37.

When the coin-engaging portion 38 of feeler 37 moves into engagement with the coin in the passageway, that coin will be held by the cradle 24. If that coin does not have an opening therethrough and if it does not have an appreciable surface deformation, the coin-engaging portion 38 of feeler 37 will slide along the surface of that coin; that coin following the rotative path of cradle 24. It will be noted that the coin and the cradle 24 were in motion relative to the feeler 37, before the coin-engaging portion 38 of feeler 37 engaged the coin; hence there is only dynamic friction rather than static friction between the coin and the coin-engaging portion 38 of feeler 37. This is desirable since dynamic frictional forces are less than static frictional forces; and the engagement of the feeler 37 with authentic coins will not unduly impede the movement of such coins.

The coin will continue to rotate with the cradle 24 without appreciable impedance until it reaches a point where the center of gravity of the coin is disposed to the right of the line connecting the projections 26 of cradle 24. At such time, the cradle will be in the coin-transferring position shown in Fig. 3; and the coin will fall onto the runway 42. The coin will then roll past magnet 44 and find its way to the coin exit 50. In dropping from the cradle 24 to the runway 42, the coin follows an approximately straight path. Consequently, the points of engagement between the coin and the coin-engaging portion 38 of feeler 37 define a bent path, as shown in Fig. 6.

If, on the other hand, the coin has an opening therethrough or has appreciable surface deformation, that coin will be caught and held by the coin-engaging portion 38 of feeler 37. The coin will be held by the cradle 24 and will be rotated past the coin-engaging portion 38; that coin-engaging portion responding to the action of weight 40 to enter the opening or the surface deformation. Thereupon, the coin will be restrained.

Gravitational forces will act upon the coin and tend to cause it to move downwardly and to the right, but the coin-engaging portion 38 of feeler 37 is inclined transversely of the coin passageway and is directed oppositely of the normal direction of movement of the coin. As a result, the coin-engaging portion 38 of feeler 37 will wedge that coin against the right hand side of the coin passageway and completely prevent further movement of that coin. If anyone were to nudge or strike the coin separator, in an effort to dislodge the coin and cause it to pass to the coin box, the nudging or striking would merely act to wedge the coin-engaging portion 38 of feeler 37 into even tighter engagement with the coin.

The coin-engaging portion 38 of feeler 37 will thus restrain coins which have openings therethrough or have

appreciable surface deformations. The restrained coins will block the coin passageway; but to clear the coin passageway, it is only necessary to depress the clearing plate 64 which acts through the recessed cam 66 to move the gate 12 outwardly away from the frame 10. The pusher bracket 56 will not move outwardly with the gate 10 but instead will remain closely adjacent the frame 10 and act to strip coins off of the end of the coin-engaging portion 38 of feeler 37. Any such coins will be acted upon by a clearing lever 68 which is pivoted on the spacer 62. Coins acted upon by the lever 68 will be directed toward the rejected coin chute 53.

The coin passageway for authentic coins extends downwardly from entrance 20 to the cradle 24, through the rotative positions of cradle 24 to runway 42, along that runway past magnet 44, and past anvil 45 and deflector 47 to runway 49 and coin exit 50. For spurious coins the coin passageways can be directed downwardly between projections 26 on cradle 24 to rejected coin chute 53, or can be from the cradle 24 to the runway 42 and past anvil 45 to stop 46 or 48 and then past deflector 51 and runway 52 to rejected coin chute 53, or can be from the entrance 20 to the cradle 24 where the feeler 37 will intercept them and then from the feeler 37 to the rejected coin chute with the assistance of clearing lever 68.

The weight 40 is the preferred biasing device for feeler 37. However, if desired, a spring or a magnetic attractive force could be substituted for the weight 40.

Whereas a preferred embodiment of the present invention has been shown and described in the drawing and accompanying description it should be apparent to those skilled in the art that various changes may be made in the form of the invention without affecting the scope thereof.

What I claim is:

1. In a coin separator which comprises a frame, a passageway for coins, and an opening adjacent one end of said passageway through which coins can be introduced into said passageway, the improvement which comprises a pivot adjacent said passageway, a feeler that is rotatably mounted on said pivot, said feeler being located exteriorly of said passageway and having a coin-engaging portion that is selectively movable into and out of said passageway, a weight on said feeler that biases said coin-engaging portion of said feeler for movement into said passageway, and a movable detent that is adjacent to said passageway and is adjacent to said feeler but that is located exteriorly of said passageway, said detent having a coin-receiving portion that extends into said passageway whenever said detent is in its initial position and having a feeler-engaging portion that is interposed between said passageway and said feeler to engage another portion of said feeler and thereby hold said coin-engaging portion of said feeler out of said passageway whenever said detent is in its initial position, said other portion of said feeler being spaced away from said coin-engaging portion of said feeler, said coin-receiving portion of said detent being movable by coins in said passageway to move said detent out of its initial position and thereby move said feeler-engaging portion of said detent away from said other portion of said feeler to permit said coin-engaging portion of said feeler to move into said passageway, a weight biasing said detent for movement toward its initial position, said feeler and said detent being so positioned that when a coin engages and moves said coin-receiving portion of said detent the said coin is in register with and will be engaged by said coin-engaging portion of said feeler, said weight on said detent generating a moment of force that is greater than the moment of force generated by the weight on said feeler.
2. In a coin separator which comprises a frame, a passageway for coins, and an opening adjacent one end of said passageway through which coins can be introduced into said passageway, the improvement which comprises

a pivot adjacent said passageway, a feeler that is rotatably mounted on said pivot, said feeler being located exteriorly of said passageway and having a coin-engaging portion that is selectively movable into and out of said passageway, said feeler being biased to move the said coin-engaging portion thereof into said passageway, and a movable detent that is adjacent to said passageway and is adjacent to said feeler but that is located exteriorly of said passageway, said detent having a coin-receiving portion that extends into said passageway whenever said detent is in its initial position and having a feeler-engaging portion that is interposed between said passageway and said feeler to engage another portion of said feeler and thereby hold said coin-engaging portion of said feeler out of said passageway whenever said detent is in its said initial position, said other portion of said feeler being spaced away from said coin-engaging portion of said feeler, said coin-receiving portion of said detent being movable by coins in said passageway to move said detent out of its said initial position and thereby move said feeler-engaging portion of said detent away from said other portion of said feeler to permit said coin-engaging portion of said feeler to move into said passageway, said detent being biased for movement toward its initial position; said feeler and said detent being so positioned that when a coin engages and moves said coin-receiving portion of said detent the said coin is in register with and will be engaged by said coin-engaging portion of said feeler.

3. In a coin separator which comprises a frame, a passageway for coins, and an opening adjacent one end of said passageway through which coins can be introduced into said passageway, the improvement which comprises a pivot adjacent said passageway, a feeler that is rotatably mounted on said pivot, said feeler being located exteriorly of said passageway and having a coin-engaging portion that is selectively movable into and out of said passageway, said feeler being biased to move the said coin-engaging portion thereof into said passageway, and a movable coin-sizing gauge that is adjacent to said passageway and is adjacent to said feeler but that is located exteriorly of said passageway, said coin-sizing gauge having a coin-receiving portion that extends into said passageway whenever said coin-sizing gauge is in its initial position and having a feeler-engaging portion that is interposed between said passageway and said feeler to engage another portion of said feeler and thereby hold said coin-engaging portion of said feeler out of said passageway whenever said coin-sizing gauge is in its said initial position, said other portion of said feeler being spaced away from said coin-engaging portion of said feeler, said coin-receiving portion of said coin-sizing gauge being movable by coins in said passageway to move said coin-sizing gauge out of its said initial position and thereby move said feeler-engaging portion of said coin-sizing gauge away from said other portion of said feeler to permit said coin-engaging portion of said feeler to move into said passageway, said coin-sizing gauge being biased for movement toward its initial position; said feeler and said coin-sizing gauge being so positioned that when a coin engages and moves said coin-receiving portion of said coin-sizing gauge the said coin is in register with and will be engaged by said coin-engaging portion of said feeler.

4. In a coin separator which comprises a frame, a passageway for coins, and an opening adjacent one end of said passageway through which coins can be introduced into said passageway, the improvement which comprises a pivot adjacent said passageway, a feeler that is rotatably mounted on said pivot, said feeler being located exteriorly of said passageway and having a coin-engaging portion that is selectively movable into and out of said passageway, said feeler being biased to move the said coin-engaging portion thereof into said passageway, and a movable detent that is adjacent to said passageway

5 and is adjacent to said feeler but that is located exteriorly of said passageway, said detent having a portion that extends into said passageway to receive coins in that passageway whenever said detent is in its initial position and having a feeler-engaging portion that can engage another portion of said feeler to hold said coin-engaging portion of said feeler out of said passageway whenever said detent is in its said initial position, said detent being biased for movement toward its said initial position, said other portion of said feeler being spaced away from said coin-engaging portion of said feeler, said coin-receiving portion of said detent being movable by coins in said passageway to move said detent out of its said initial position and thereby move said feeler-engaging portion of said detent away from said other portion of said feeler to permit said coin-engaging portion of said feeler to move into said passageway, said feeler and said detent being so positioned that said coin-engaging portion of said feeler is held out of said passageway until after a coin strikes and moves said coin-receiving portion of said detent, said coin-engaging portion of said feeler being inclined of said passageway in all moved positions of said feeler.

5. In a coin separator which comprises a frame, a passageway for coins, and an opening adjacent one end of said passageway through which coins can be introduced into said passageway, the improvement which comprises a pivot adjacent said passageway, a feeler that is rotatably mounted on said pivot, said feeler being located exteriorly of said passageway and having a coin-engaging portion that is selectively movable into and out of said passageway, said feeler being biased to move the said coin-engaging portion thereof into said passageway, a second pivot adjacent said passageway and adjacent said feeler, and a coin-sizing cradle that is rotatably mounted on said second pivot and that is located exteriorly of said passageway, a coin-receiving surface on said cradle that extends into said passageway to intercept coins whenever said cradle is in its initial position and to free those coins whenever said cradle has rotated to coin-freeing position, said cradle having a feeler-engaging portion that can engage another portion of said feeler to hold said coin-engaging portion of said feeler out of said passageway whenever said cradle is in its said initial position, said cradle being biased for movement toward its said initial position, said other portion of said feeler being spaced away from said coin-engaging portion of said feeler, said coin-receiving surface of said cradle being movable by coins in said passageway to move said cradle toward coin-freeing position and thereby move said feeler-engaging portion of said cradle away from said other portion of said feeler to permit said coin-engaging portion of said feeler to move into said passageway, said feeler and said cradle being so positioned that said coin-engaging portion of said feeler is held out of said passageway until after a coin strikes and moves said coin-receiving surface of said cradle, the movement of said cradle from its said initial position to said coin-freeing position while said coin-engaging portion of said feeler is in register with said coin enabling said coin-engaging portion of said feeler to explore a bent path on the surface of said coin.

6. In a coin separator which comprises a frame, a passageway for coins, and an opening adjacent one end of said passageway through which coins can be introduced into said passageway, the improvement which comprises a pivot adjacent said passageway, a feeler that is rotatably mounted on said pivot, said feeler being located exteriorly of said passageway and having a coin-engaging portion that is selectively movable into and out of said passageway, a weight on said feeler that biases said coin-engaging portion of said feeler for movement into said passageway, and a movable detent that is adjacent to said passageway and is adjacent to said feeler but that is located exteriorly of said passageway, said detent

having a coin-receiving portion that extends into said passageway whenever said detent is in its initial position and having a feeler-engaging portion that can engage another portion of said feeler to hold said coin-engaging portion of said feeler out of said passageway whenever said detent is in its said initial position, said other portion of said feeler being spaced away from said coin-engaging portion of said feeler, said coin-receiving portion of said detent being movable by coins in said passageway to move said detent out of its said initial position and thereby move said feeler-engaging portion of said detent away from said other portion of said feeler to permit said coin-engaging portion of said feeler to move into said passageway, a weight biasing said detent for movement toward its said initial position, said feeler and said detent being so positioned that said coin-engaging portion of said feeler is held out of said passageway until

after a coin strikes and moves said coin-receiving portion of said detent, said coin-engaging portion of said feeler being inclined of said passageway and being directed oppositely of the path of movement of coins in said passageway in all moved positions of said feeler.
